UNITED STATES PATENT OFFICE.

JOSEPH P. BAUMGARTNER, OF PHILADELPHIA, PENNSYLVANIA.

GARMENT-SECURING BAND.

1,174,926.

Specification of Letters Patent.

Patented Mar. 7, 1916.

Original application filed July 5, 1910, Serial No. 570,280. Divided and this application filed September 15, 1910. Serial No. 582,182.

To all whom it may concern:

Be it known that I, JOSEPH P. BAUMGARTNER, a citizen of the United States, and a resident of Philadelphia, Pennsylvania, have invented a certain new and useful Garment-Securing Band, of which the following is a specification.

My invention relates to bands either for belt or garter use, and particularly to such belts as are used by ladies to hold a shirt-waist in and down at the bottom, with provision for dipping the front of the belt to increase the apparent waist length and to produce or improve the modish figure and effect, and to such garters as are worn by men.

One of the purposes of my invention is to provide adjustment for one end or, if preferred, for both of the ends of the band. 20 This is done through a terminal loop or terminal loops of the band. The loop or one of the loops is adjustable. I encircle one side of one loop back of the extreme end thereof and stiffen and support the end or 25 ends of the loop or loops. When the adjustable loop is taken, the encircling support forms a ridge upon the side of the loop, following the adjustment and distributing the wear.

30 A further purpose of my invention is to provide metal terminals for the band, to support one of the terminals from the band by engaging it therewith at points spaced along the length of the band and to secure a garment attaching device upon the terminal between its two points of support and, preferably, between the turns of a protecting loop.

I have attained these and other objects of 40 my invention pointed out in the specification and particularly in the claims thereof by the construction herein shown which presents those forms thereof which have proved most practical and successful and best adapted for commercial use.

Figure 1 is a perspective view of a ladies' belt embodying my invention. Fig. 2 is a broken perspective view of Fig. 1 in process of adjustment. Fig. 3 is a broken perspective view of a structure similar to that of Fig. 1. Fig. 4 is a perspective view of the terminals used in Figs. 1 and 2. Fig. 5 is a section of a part of the structure of Fig. 2 upon line x-x thereof. Fig. 6 is a perspective view of a buckle used by me. Fig.

7 is a broken elevation of my band and garment support in garter form.

My invention is a continuation for certain purposes of an application filed by me July 5th, 1910, Serial No. 570,280, for garment 60 securing belt, containing matter divided out from that application upon requirement for division.

10 is a belt or band of any suitable material, elastic or inelastic, which, in the form 65 shown in Fig. 1, I illustrate as readily adjustable by means of the buckles 11, retaining the ends of loops, comprising inner sides 12, 13 and outer terminal sides 14, 15.

As illustrated in Fig. 3, but one such loop 70 need be made use of, the two being provided so that the junction point may be maintained at the center without necessity for shifting the belt about the waist. It is also advantageous for ease and convenience of access 75 and greater range of adjustment.

The engaging, preferably metallic, terminal members 16, 17, comprising garment connecting members, are shown as slidable upon one side each of the respective loops 80 in the form shown in Fig. 1, and are shown as carrying a hook 18 for engagement with an eye 19, my preferred type of engaging devices.

The members 16, 17 are shown as provided with lateral projections 20, 21 reversely turned to form openings or passages 22, 23 to encircle preferably the outer sides, in this illustration the terminal sides 14, 15, of the loops without engaging them tightly. 90 I prefer to make this the only engagement of the member 16 with its end of the belt or band, but to pass the other end of the belt or band through the eye 19 in addition to passage through the opening or passage 95 23, in order that the plate 17 may be supported by the belt or band at both ends of the plate.

I have shown three slightly different forms of plate in Figs. 3, 4 and 7, differing 100 only in the number and location of slots for a garment engaging device such as 24, making use of two slots therefor in the form used in Figs. 1, 2, 4 and 5, a single approximately central slot in Fig. 3 and a side slot 105 in the form of Fig. 7 to reduce the thickness of material there used. This plate 17 in each case supports a garment engaging device differing according to the character of garment with which it is intended to en- 110

gage and the hold to be had thereon, making use of a tape 24' in Fig. 3, and a tape 24² with clasp 24³ in Fig. 7. In the ladies' belt form I prefer to surround the upper edge 5 of the plate as at 25 to conceal it and to protect the fabric of the waist from engagement with the metal. In this form I show the tape as made up of a strip of material which passes through the slots 26, 27, 10 starting from either front or back as preferred. The limitation of the tape by the side walls of the slots 26, 27 prevents lateral movement of the tape upon the plate. This is best seen in Fig. 5. I show the ends of 15 the device as fastened together at any suitable point, such as 28, and it may be sewed through from side to side of the device, as seen at 29 in Fig. 1, using additional stitching for this purpose, if desired. The garment 20 fastening device forms a depending loop or member which can be secured to the clothing at this point to hold or pull the band or belt modishly, in the case of the ladies' belt, and to hold the stocking or 25 other garment up in the case of the garter.

In the structures shown in Figs. 3 and 7, it is the intention to adjust one end only, in this case the right-hand end, and I have shown the same form of adjustment for it 30 as in the other figures. In order to cover the back of the plate 17 and at the same time form a proper fastening for the left-hand end of the belt or band, I loop this non-adjustable end also. For this purpose I pass 35 the body of the belt through the openings 23 and 19, passing it at 30 in front of this plate, and bringing its end around to the back of the plate at 31, to be introduced between the plate 17' and the portion 30, as 40 at 32, so that the end of the band is held therebetween.

In the form shown in Fig. 3, I pass the loop 24' through the single slot 33 of the plate 17', but may locate this slot in other 45 positions, as at 34 in the form shown in Fig. 7. The advantage of this latter form is that the thickness of the fabric and plate are not increased by the fabric of the garment 50 securing device 24², which terminates below the fabric of the belt.

In making the adjustment of the belt, I prefer to secure the buckle 11 to the fabric of the belt near the end thereof, and do so, in the form shown, by means of openings 35 through which the fabric is sewed to the buckle. This retains the buckle at a fixed 60 position from the end 36 of the fabric which is purposely extended beyond the buckle in order to form a tab by which the buckle may be drawn to the position of Fig. 1 after the portions 14, 15 have been pulled in the direction of the arrows adjacent them in Fig. 2 to secure the desired tension of the belt. It will be seen that the portions 14, 15 can 65 readily be engaged by the fingers, either to

take up the belt in the direction of the arrows to tighten it, or by pulling it in the reverse direction to move the buckles 11, causing a slackening of the belt.

In all of the forms I prefer to attach my 70 garment securing device between the points at which it receives direct support from the loop, and this is true as to all of the structures illustrated. The garment attaching device 24, 24', and 24² is thus suspended between two points of support upon the belt 75 in all of these, my preferred forms.

Other forms of engaging members within the scope of my disclosure and claims may evidently be applied to obtain some or all 80 of the advantages of my invention and, in general, I desire not to be restricted to the exact forms or arrangements of any of the elements or features shown.

While the form shown in Fig. 3 is intended 85 for use primarily in connection with shirtwaist retention and arrangement, my invention is much broader than this and applies generally to bands suspending garment retaining devices. Though not attempting to show all the forms in which this may occur, I have endeavored to make the broader application clearer by illustrating one other form in which such a surrounding band is made to support a garment, applying the invention to the familiar support of men's half hose in garter form, 95 as seen in Fig. 7.

Having thus described my invention, what I claim as new and desire to secure by Letters Patent is:

1. A garment securing band having a loop at each end thereof, a garment-connecting member freely surrounding the fabric of one loop at the end and having lateral portions 105 reversely turned to surround the fabric of the loop at a distance from the end and independent means for adjusting the end of one of the loops, whereby the adjustment of the loop may be varied readily while the 110 band is in place.

2. A garment securing band terminating at one end in a loop, an adjustable fastening for the loop, a plate partly surrounded by the loop, said plate having an opening at 115 each end for free passage of the fabric of the loop, permitting the plate to ride freely upon the loop, one of the openings being parallel to the length of the band and the other at the end of the loop, whereby the 120 loop may be adjusted readily with the band in place, a garment-securing device attached to said plate between the openings, and a hook member secured to the other end of the band to engage with one of said openings. 125

3. A garment securing band having an adjustable fastener for one end of the band upon the body thereof to form a loop, a terminal plate riding upon said loop to permit free adjustment of the loop therethrough 130

while the band is in place, said plate having openings for the band, one parallel to the plane of the band and the other transverse thereto, so that the fabric loop covers 5 the intervening portion of the plate, said plate also having a longitudinal opening between the two previously named openings, a garment securing device passing through said longitudinal opening and a terminal for 10 the other end of the band for engagement with said plate.

4. In a device of the character stated, a plate having an eye at one end and reversely turned lateral extensions forming a passage 15 at the other end, one end of a band passing through the passage and eye freely in the direction of the axis of each, an adjustment for the end of said band to form a loop, a depending garment securing device passing 20 between the band and plate and secured to the plate and a hook secured to the other end of the band and adapted to engage within the eye.

5. A garment securing band having a loop 25 at one end thereof, a garment-connecting member freely surrounding the fabric of said loop at the end and reversely turned to form an opening in the direction of the length of the loop to surround the fabric of 30 the loop at a distance from the end, and independent means for adjusting the length of the loop whereby the adjustment of the band

may be effected readily by varying the length of the loop while the band is in place.

6. A garment securing band having a loop 35 at one end thereof, a garment-connecting member freely surrounding the fabric of said loop at the end and reversely turned to form an opening in the direction of the length of the loop to surround the fabric of 40 the loop at a distance from the end, independent means for adjusting the length of the loop whereby the adjustment of the band may be effected readily by varying the length of the loop while the band is in place 45 and a garment securing device depending from the garment connecting device.

7. A garment securing band terminating at one end in a loop, adjusting means for the loop to vary the effective length of the 50 band, a garment securing plate having an eye transverse to its general plane, through which the end of the loop passes and reversely extending side portions forming an opening parallel to the plane of the plate, 55 so that the plate rides upon the end of the loop with support at two spaced points and with the body of the plate covered by the loop therebetween and a depending garment securing device connected to the plate.

JOSEPH P. BAUMGARTNER.
